Specification of Letters Patent.

Patented Nov. 3, 1914.

Application filed June 23, 1911. Serial No. 634,999.

To all whom it may concern:

Be it known that I, LINN BOYD BENTON, a citizen of the United States, residing at Plainfield, in the county of Union and State 5 of New Jersey, have invented certain new and useful Improvements in Type-Casting Machines, of which the following is a specification, reference being had to the accompanying drawing, forming a part thereof.

10 This invention relates to type-casting machines of the character illustrated and described in United States Letters Patent Nos. 376,765 patented January 24, 1888, and 392,710 patented November 13, 1888, to The

15 Cincinnati Type Foundry as assignee of Henry Barth and Ernst Lietze, and reference may be had to the said Letters Patent for specific information as to the general features of construction and arrangement of 20 parts of the machine referred to in this specification and which are not specifically illustrated by the drawings which form a part of this specification, and which are not specifically described in this specification.

25 The objects of this invention are to improve type-casting machines of the general character illustrated and described in the United States Letters Patent hereinbefore referred to, so that they can be run at a 30 higher speed with an increased output of type as compared with the older forms of machines for the same period of operation, and to improve the construction of such type-casting machines in the manner to be 35 hereinafter specifically described and claimed.

Referring to the drawings which accompany this specification and form a part thereof, which drawings illustrate embodiments of this invention and on which drawings the same reference characters are used to designate the same elements wherever they may appear in each of the several views, Figure 1 is a front elevation of part 45 of a type-casting machine, a part being broken away to show clearly the construction of a part of the machine; Fig. 2 is a front elevation of part of the machine, parts being broken away and parts being shown 50 in section, the view being similar to the view shown by Fig. 1, but showing movable parts of the machine in different positions from the positions which the said movable

parts occupy in Fig. 1; Fig. 3 is a rear elevation of part of the machine; Fig. 4 is a plan view on a somewhat larger scale of a part of the machine taken on the line *a—a*, Fig. 1; Fig. 5 is a plan view of a part of the machine taken on the line *b—b*, Figs. 2 and 3; Fig. 6 is a vertical section of a detail, 60 taken on the line *c—c* on Fig. 4; Fig. 7 is a horizontal section of a detail; Fig. 8 is a vertical section taken on the line *d—d* on Fig. 9; Fig. 9 is an elevation, partly in section, taken on the line *e—e* on Fig. 8; and 65 Fig. 10 is an elevation, partly in section, of a detail.

Referring specifically to the drawings, the reference numeral 1 designates the mold-beam of the machine, 100 the mold, 2 the reciprocative mold-cover, which is reciprocated back and forth on the stationary mold-beam 1 and over the top of the mold 100 by the connecting rod 3, which is moved by mechanism not shown by the drawings accompanying this specification, but which is well known to those skilled in the art and which can be readily understood by reference to the United States Letters Patent 75 hereinbefore referred to.

The reciprocative mold-cover 2 is moved back and forth on the top surface of the mold-beam 1, which is level with the top face of the stationary parts of the mold, in the ordinary manner, and the mold-cover 2 is retained in place laterally by the plates 4 and 5, which are securely fastened to the mold-beam 1 by screws, as shown by the drawings. The mold-cover 2 is provided with a guide member 6 projecting from each 90 side thereof, and extending rearwardly therefrom. These guide members 6 have their opposite faces parallel and these faces slide accurately between the plates 4 and 5. Secured on the tops of the plates 4 and 5 and extending partly over the guide members 6 are holding-down plates 7 and 8.

The mold-cover 2 is provided on its top with a yoke 9, in which is pivoted a lever 10 provided at one end with the anti-friction roller 11, which is adapted to ride under the cam bar 12 which is rigidly supported in a fixed position by the standard 100 13, which in turn is adjustably secured to the rear plate 5. Between the anti-friction 105 roller 11 and the stud 14 is a pivot 15, on

which is pivoted a rod 16, which is guided at its lower end in the mold-cover 2 so as to be retained in position while being free to move up and down, and surrounding said rod 16 and retained between the head 17 on said rod and mold-cover 2, is a spiral spring 18 of the open or compression type, which is constantly exerting its force to elevate the end of the lever 10 to which the anti-friction roller 11 is attached. The end of the lever 10 on the other side of the pivot 14 from the anti-friction roller 11 extends above a shoulder 19 formed on a plunger 20, which plunger will be hereinafter described more at length and which is capable of vertical inmovement.

The mold-cover 2 is provided with a pin 21 to serve as a stop, and an adjusting screw 22 provided with a lock nut 23, is received within a screwthreaded aperture in lever 10 in line with pin 21. The screw 22 can be so adjusted with respect to the lever 10 that when screw 22 contacts with pin 21, the downward movement of plunger 20 under the influence of spring 18 is accurately determined.

Fig. 1 of the drawings shows the movable parts of the machine in the positions which they occupy when a type is being cast and when a type is being discharged into the channel to be hereinafter described, and the cam surface of cam bar 12 is so proportioned that when the parts are in the positions shown the anti-friction roller 11 does not touch the cam bar 12, as clearly shown by the drawings.

Fig. 2 of the drawings shows the movable parts of the machine in the positions which they occupy when a type has been cast and has just been freed from the mold and matrix, and in these positions of the parts it will be observed that the anti-friction roller 11 has rolled under the cam bar 12 and has been forced down so that the screw 22 no longer contacts with the pin 21 and the plunger 20 has been able to assume a more elevated position.

The machine is provided as usual with an upright 24 removably attached to the mold-beam by a bolt passed through a transverse bore or opening formed as indicated in Figs. 1 and 9, and held in line by a feather. It is also provided with the usual plate 58 (commonly called nick guide) securely fastened to the mold-beam extending over and covering the right hand end of the mold and forming an end wall with its upper edge practically in line with the top of the mold (see Figs. 1, 2 and 5). Facing the nick guide 58 is an upright member 25, which is held in place laterally by guide fingers 26 and is supported from upright 24 by pins 27 and 28, which are immovably fastened to the upright member 25, but are slidable longitudinally in bore holes in upright 24, and

which are pushed toward the nick guide 58 by spiral springs 86, 87, and which can be drawn back and held back against the tension of the said springs by means of the thumb nuts 29 and 30, which are screwed onto the screw-threaded, reduced ends of said pins 27 and 28 respectively, in the ordinary manner.

The upright member 25 and the nick guide 58 form a channel 31 in which the type are firmly held for grooving out the jet and trimming or rubbing by the knives 32 and 33, in the ordinary manner, and a part of this invention relates to this channel 31, as will hereinafter be more fully explained and described. The type after passing between the knives 32 and 33 are pushed out from the tight channel 31 into a free or loose channel 34, from which they pass onto carrying sticks in the well known manner.

The case 35 is immovably secured to the upright 24, as shown in Figs. 8 and 9, and the slideable jaw bar 36 is reciprocal within the same in the ordinary manner, and abuts against the mold-cover 2, as shown in Fig. 1 where the adjusting screw in the lug 78 forming a part of the slideable jaw bar is illustrated, except when the mold-cover 2 is at its extreme limit of movement away from the channel 31, as clearly shown by Figs. 2 and 3 of the drawings. The immovable upright 37 supports a rocker shaft 38, to which the crank arm 39 is securely fastened so as to rock the same, and the crank arm 39 is actuated by the connecting rod 40 which is pivoted thereto.

As shown in Figs. 1, 2, 4, 6 and 7, the clamp 41 is bifurcated or formed with two arms 44 and 45, which are adapted to seat upon a saddle member 46, secured to the top of the mold-cover 2, in order to clamp the mold-cover tight upon the mold during the casting of a type when the molten type metal is forced in the usual manner into the mold by the pump (not shown). The clamp is also formed with a cylindrical stem 88 fitted in a corresponding bore in the boss 43 on one end of the rocker shaft 38 and having a reduced threaded end 42 provided with a nut by which it is firmly fastened in said boss transversely to said shaft. Screws 47 and 48, threaded in the boss 43, with their heads overhanging and engaging seats on the clamp 41 above and below the center of the stem 88, afford means for turning the clamp about the axis of said stem when the nut thereon is loosened, and thus accurately adjusting the arms 44 and 45 vertically so that they will bear with equal pressure on opposite ends of the saddle member 46. A lifting member 49 is secured to the top of the boss 43 and is provided with a projecting toe 50, which when the parts are in the position to discharge a type, which has been

molded, into channel 31, extends under a projection 51 on plunger 20.

The immovable upright 37 guides a vertically movable plunger rod 52, which carries at its upper end an anti-friction roller 53. This plunger rod 52 with the anti-friction roller 53 thereon is intended to force the plunger 20 downwardly to force a type, held between the mold-cover 2 and the slideable jaw bar 36, down into the channel 31, in a manner to be hereinafter described.

The plunger 20 is movable vertically within a recess or cavity 54 within the mold-cover 2, and a pusher plate 55 is secured to the plunger 20 and extends below the lower end thereof and is long enough and there is sufficient play between the lower end of the plunger 20 and the cavity or recess 54 so that when the plunger 20 is moved downwardly, the pusher plate 55 can be moved below the lower surface of the mold-cover 2 and slightly into channel 31 when the movable parts of the machine are in the positions shown by Fig. 1 of the drawings. A spiral spring 56 normally pushes the plunger 20 upwardly and holds the pusher plate 55 elevated above the bottom of the mold-cover 2, and as is customary in this class of machines, the spring 56 is weaker than the spring 18. The spring 18 is the operating member which forces plunger 20 and pusher plate 55 downwardly so that a type is securely held both between the jaws composed of the mold-cover 2 and the slideable jaw bar 36 and between pusher plate 55 and the top of the mold.

Type-casting machines of the character described in this specification and the United States Letters Patent referred to herein, have to be made very carefully with the parts fitting as accurately as in high class scientific instruments, and while it is possible to make the machines practically perfect, the actual use of the machines will of course destroy the original accuracy of construction. In other words, the machines will wear out and there will come a time when parts will have to be discarded and renewed, or the parts resurfaced or refinished, but the adjustment provided for by the screws 47 and 48 in the boss 43 not only enables the arms 44 and 45 to be set originally to bear equally upon both ends of the saddle member 46, but these screws 47 and 55 48 provide for taking up looseness due to wear on one side or the other of the bottom of the mold-cover 2 or the top of the mold.

When running type-casting machines of the character described in this specification at a high rate of speed, it has been found difficult to transfer or push a type from between the carrying jaws formed by the end of the mold cover 2 and the slideable jaw bar 36 into the channel 31 by means of the pusher plate 55 and to withdraw the pusher

plate 55 out of the channel 31, without mishap. In type-casting machines of the same general character as that illustrated by the drawings accompanying this specification and more specifically illustrated and described in the United States Letters Patent hereinbefore referred to, a type which had been cast was carried forward from a point over the mold to the tight vertical channel designated on the drawings by the reference numeral 31, by the reciprocating movements of the mold-cover 2 and the slideable jaw bar 36, and the overthrow movement of these members at the end of the stroke was generally limited by a positive stop. The pusher plate 55 then pushed the type down into a tight channel, the channel being as tight as the springs behind the upright member 25 pressing against a column of type in the tight channel could make it. If the old style machines did not run too rapidly, a type would be delivered in the tight channel and the pusher plate 55 would retreat until stopped by plunger 20 coming in contact with lever 10, said lever 10 having been previously adjusted to the proper set in the manner well known to those skilled in the art. A spring, like or similar to the spring 56, shown by the drawings accompanying this specification, was relied upon in the prior machines to lift the pusher plate 55 up out of the tight channel and to its extreme upward limit of movement. If the type-casting machines of the prior art were run so fast that the spring 56 would not act quickly enough to lift the pusher plate 55 out of the tight channel, the pusher plate 55 would be caught in the tight channel and bent or broken as the mold-cover 2 and the slideable jaw bar 36 moved to the left (see Fig. 1 of the drawings). This invention guards against any such accident because the pusher plate 55 is positively lifted out of the channel and even with the top of the mold by the lifting member 49, which is provided with the projecting toe 50 and which positively lifts the pusher plate 55, as hereinbefore described. Another source of trouble with the type-casting machines of this general character of the prior art, is experienced when a little too much oil has been placed on top of the mold to prevent cutting. This oil gets onto the bottom of the pusher plate 55 and when a type was pressed down on top of the mold by pusher plate 55, a thin film of oil remained between the type and the pusher plate 55, and this oil remained there until the type was carried over to the tight channel and the pusher plate 55 had pushed the type down into the tight channel, but as the friction between the type and the tight channel was not always enough to detach the type from the bottom of the pusher plate 55 to which the type stuck on account of the aforesaid film

of oil, the type would sometimes cling to the pusher plate and be lifted up with the pusher plate out of the tight channel and would be carried along to the left (see Fig. 5 1 of the drawings) on top of the mold in which a new type had been cast, so that when the new type which had been cast was discharged from the mold, there would be two type, one on top of the other, and the 10 machines were not constructed to handle two type superimposed in this manner, and an accident would result, which generally required a stoppage of the machine for repairs.

15 This invention guards against a type sticking to the pusher plate 55 in the manner hereinbefore described, because the upward movement of the pusher plate 55 after it has pushed a type into the loose channel 20 57, is limited by the movable plunger rod 52 and the anti-friction roller 53, to the height of the top of the mold, and the several parts are so timed in their relative movements that the bottom of the pusher 25 plate 55 is only raised to the height of the top of the mold until the mold cover 2 is moved far enough to the left (see Fig. 1 of the drawings) for the plunger 20 to be moved out from under the roller 53, so that 30 if a type sticks to the bottom of the pusher plate 55 it will be wiped or scraped off from the bottom of the pusher plate 55 as the pusher plate 55 moves to the left (see Fig. 1 of the drawings) away from the 35 loose channel 57. The movement of the slidable jaw bar 36 to the left (see Figs. 1 and 2) is limited by the nut 90, being adjusted in such a manner that the said movement ceases just before the end of the slidable jaw bar 36 reaches the opening in the 40 mold. This affords an ample opening for the newly cast type to enter when pushed out of the mold by the body plate 101. It also allows the type to be detached from 45 the end of the body plate 101 by the movement of the mold cover 2 to the right (see Figs. 1 and 2) before the type touches the jaw bar 36 in the well known manner. Moreover, in running the machine at a 50 high speed the *vis viva* of the reciprocating parts, viz: the mold-cover 2 and the parts carried thereby and the connecting rod 3, is such as to cause an overthrow of the mold-cover 2 at both ends of its stroke. This 55 overthrow is not objectionable when the mold-cover 2 is being moved toward the left hand, when looking at Figs. 1 and 2 of the drawings, but when the mold-cover 2 is being moved toward the right hand, serious 60 difficulty is encountered in transferring type from between the jaws formed by the end of the mold-cover 2 and the slidable jaw bar 36 into the channel 31. This invention overcomes this difficulty by beveling off 65 the top edge of the upright member 25 as

clearly shown by Figs. 1 and 2 of the drawings, thereby increasing the width of the channel 31 at the point where the type are delivered into the said channel 31, so that in effect the type are delivered one by one as 70 they are cast into a loose channel 57 before they are forced into the tight channel 31. The type are cast with nicks and the nick guide 58, which as usual forms one side of the loose channel 57 and the tight channel 75 31, holds the type in proper register and alinement while they are being grooved on the bottom and shaved in passing through the tight channel 31. In order to move the type in the loose channel 57 against the 80 nick guide 58, a pusher 59 is employed which may conveniently be constructed as a block seated in a slot 60, cut in the upper part of the upright member 25, and provided with a pin 61 which projects through 85 the block on both sides thereof and is received within recesses 62 and 63 cut in the rear part of the upright member 25, as clearly shown by the drawings. The block of the pusher 59 is provided with an extension 64 which is provided with a reduced portion 65, which are received within bores 66 and 67. A spring 68 is located in bore 66 and bears against the end thereof, surrounds the reduced portion 65 of the extension 90 95 64 and bears against the shoulder on extension 64 to press the pusher outwardly. The pusher is also provided on its top with a projection 69 which is received within a slot 70 cut in the under face of the slidable 100 jaw bar 36 and which slot is of such length that the slidable jaw bar 36 can move to its extreme position toward the left, Figs. 1 and 2, without the end of the slot contacting with projection 69, but when the slidable jaw bar 36 is moved to its extreme 105 right hand position, Figs. 1 and 2, the end of the slot 70 contacts with the projection 69 and forces the pusher to the right against the tension of its spring 68, so that 110 the whole width of the loose channel 57 formed by the beveling off of the upper part of upright member 25 is left clear for the type to fall or be pushed into. When the slidable jaw bar 36 moves back again 115 toward the left, the spring 68 shoves the pusher toward the left and joggles the type over against the nick guide 58 with the nick of the type engaged therewith. The pin 61 limits the movement of the pusher 59 toward the left and it is preferred that the extent of movement allowed the pusher 59 is such as to push the type within a very small distance of the left hand side of the loose channel 57. The beveled upper end of 120 the upright member 25, whereby the loose channel 57 is formed, is preferably of a depth sufficient to take in several type, as clearly shown by Figs. 1 and 2 of the drawings, and by the pusher 59 being limited 125 130

in its movement so as not to be able to push the last type delivered to the loose channel 57 clear over to the left, the type in the loose channel will be successively tapped by the pusher 59 as each new type is deposited in the channel, and if a type should not be deposited in the channel with its nick in exact alinement with the nick guide 58, this successive tapping of the type in the channel as each new type is deposited therein, will cause that type to be moved lengthwise as the nick guide 58 engages with its nick, so that when the type reaches the top part of the tight channel 31 the type will be in proper alinement with the nick guide 58. The pusher plate 55 must move down between the ends of the mold-cover 2 and the slidable jaw bar 36 in the well known manner, but its upward stroke consists of two motions, first to top of mold and then to higher position, and at the same time a type which is being moved from the mold to the channels 57 and 31 must be held securely, but without being pinched, because the type in its movement is carried against a jet breaker 71 which is a knife which cuts the jet 72 off from the foot of the type 73, and between shaving or rubbing knives 74 and 75, which shave or rub the bur from two edges of the type, the burs on the other two edges of the type being shaved or rubbed off by the knives 32 and 33 as the type pass through the tight channel 31, so the screw 76, provided with a lock nut 77, is screwed through a screw threaded aperture in the lug 78 on the top of the slidable jaw bar 36 to determine the closeness of approach of the end of the slidable jaw bar 36 to the pusher plate 55. It will be understood of course, that the slidable jaw bar 36 is forced to the left, Figs. 1 and 2, by a spring 89 in the ordinary manner, and it is pushed to the right against the tension of such spring by the end of the mold-cover 2 bearing against the end of screw 76.

In the use of type-casting and finishing machines of the character described in this specification, shavings of type metal and thin fins of type metal sometimes get between the movable and the stationary parts of the machine, and the pusher 59 is preferably bifurcated as clearly shown by Fig. 5 of the drawings, and fits loosely within the slot 60 so that there is plenty of clearance for any shavings or fins to escape, and the lower part of slot 60 is inclined away from the loose channel 57 so that any shavings or fins of type metal will drop clear of the type and will not be carried down with the type into the tight channel 31. When running type-casting machines of the character described in this specification at high speeds and more particularly when casting small bodied type, great difficulty has been experienced because the jets 72 on

the type when broken off by the jet breaker 71, would fly all about the machine and create a general clutter. This difficulty has been obviated by providing a cage 79 secured to the mold-cover 2 and inclosing the jet 72. As shown by the drawings, this cage is composed of a member 80 with an outstanding part 81 on top of which is secured a plate 82 with its end 83 bent down, as clearly shown by Fig. 3 of the drawings, and a space 84 (see Fig. 5) is provided within which the jet breaker knife 71 can extend to cut off the jet 72. The movement of the mold-cover 2 and the cage 79 to the left, as shown in Figs. 3 and 5 (to the right relative to Figs. 1 and 2) carries jet 72 over a pipe or chute 85 into which jet-chute or pipe the jet will drop and through which the jets can be conducted to any convenient point of discharge.

All unnecessary illustration of the details of the machine have been avoided, as they are well known and are illustrated and described in the United States Letters Patent hereinbefore referred to, and in describing the operation of the machine the parts not shown and their function will be only generally referred to for the purpose of making clear the improvements described in this specification and illustrated by the drawings accompanying the same.

The operation of the machine is as follows: Referring first to Fig. 2 of the drawings, the parts are shown in the positions which they occupy immediately after a type has been cast and a type has been raised by the body plate 101 from within the mold to the level of the top of the mold 100. This type is designated by the reference numeral 73. The mold-cover 2 is now moved to the right by the connecting rod 3, moving with it the slidable jaw bar 36 as soon as the end of the mold-cover 2 contacts with the end of the screw 76. It is, of course, understood, as hereinbefore explained, that when the slidable jaw bar 36 is moved to the left by spring 89 (following the movement of mold-cover 2 to the left) its movement to the left is stopped by nut 90 contacting with the end of case 35 in the ordinary manner. During this movement the anti-friction roller 11 rolls out from under the influence of the lower cam edge of cam bar 12 and the spring 18 being more powerful than the spring 56, swings lever 10 upon its pivot 14 and forces plunger 20 down, bringing the pusher plate 55 down into substantial contact with type 73, but the screw 22 having been adjusted properly, comes in contact with the pin 21 so that the tension of spring 18 cannot force the plunger 20 upon the type 73 with force enough to destroy or injure the type. As the mold-cover 2 is moving toward the right, the saddle member 46 is being brought under the arms 44

and 45 of the clamp 41, and when the mold-cover 2 is moved to its extreme limit of motion to the right, the connecting rod 40 has been moved up, swinging up the crank 5 arm 39 and depressing the arms 44 and 45 of the clamp 41 onto saddle 46, and thereby clamping the mold-cover 2 tightly against the top of the mold, because it is when the parts are in this position that the pump 10 (not shown) is forcing liquid type metal into the mold to cast a new type. Before the mold-cover 2 has reached its extreme limit of movement toward the right, the end of the slot 70, in the slidable jaw bar 36, 15 contacts with the projection 69 on the pusher 59 and further movement toward the right moves the pusher 59 to the right, so that the entire width of the loose channel 57 is exposed for the reception of the type 73. As 20 the arms 44 and 45 of the clamp 41 were swung down toward and upon the saddle member 46, the lifting member 49 swung down with the said arms so that its toe 50 was below the projection 51 on the plunger 25 20 and the projection 51 on the plunger 20 was carried over the toe 50 of the lifting member 49 as the mold-cover 2 moved toward the right. This same movement carried the cage 79 (see Fig. 3 of the drawings, 30 which is a rear elevation of a part of the machine and the right and left hand sides of the machine are consequently reversed) in the same direction, or to the right hand when looking at Figs. 1 and 2. The plunger 35 rod 52 with its anti-friction roller 53 is so timed as to move down and force plunger 20 down when the type 73 and pusher plate 55 are above and opposite the loose channel 57, and the extent of this movement is such that 40 the pusher plate 55 descends into said loose channel 57 so as to insure the removal of the type from the loose jaw formed by the ends of the mold-cover 2 and the slidable jaw bar 36 into the loose channel 57. It 45 will be understood that at this time in the operation of the machine a new type has been cast in the type mold and type 73 has been deposited in the loose channel 57 and the cycle of operation of the machine is completed by the parts returning from the position 50 shown by Fig. 1 of the drawings to the position shown by Fig. 2 of the drawings. This return action is accomplished in the following manner: The arms 44 and 45 of 55 the clamp 41 are released from saddle 46 by a downward movement of the connecting rod 40 and at the same time the toe 50 of the lifting member 49 is lifted up, (and provided spring 56 does not act) positively 60 raising plunger 20 and withdrawing the pusher plate 55 completely out of the loose channel 57 with its lower end even with the top of the mold. It should be stated now that the plunger rod 52 with its anti-friction 65 roller 53 has commenced to rise either

before or at the same time with the movement of the arms 44 and 45 of the clamp 41, and Fig. 1 of the drawings shows the plunger 20 as resting against the anti-friction roller 53. When the pusher plate 55 70 has been lifted entirely out of the loose channel 57 with its lower surface even with the top of the mold, the mold-cover 2 is pulled to the left by the connecting rod 3 and the spring 89 causes the slidable jaw 75 bar 36 to follow the mold-cover 2 to the left. This movement permits the pusher 59 to also move to the left to its extreme limit of movement. As this movement of the mold-cover 2 to the left continues, the anti-friction roller 80 11 rides under the cam bar 12, thereby compressing spring 18 and permitting the plunger 20 to rise so that it will be above the top of the newly cast type, when the type is raised to the level of the 85 top of the mold by the body plate 101, as clearly shown by Fig. 2 of the drawings, and the plunger rod 52 with its anti-friction roller 53 have continued to rise, after stopping at a point to hold the bottom of the 90 pusher plate 55 even with the top of the mold until the plunger 20 has moved out from under the anti-friction roller 53, during the movement of the mold-cover 2 to the left, until the parts are in the position 95 shown by Fig. 2 of the drawings, when the direction of movement of the mold-cover 2 is reversed and the cycle of operations is repeated.

It will be observed that the mold-cover 2 100 is only clamped tightly against the mold-beam 1 by the clamp 41 when in a condition of rest and that the pusher plate 55 only rises out of the loose channel 57 far enough to clear the top of the mold so that if a type 105 sticks to it, which will sometimes happen, the type will be scraped off into the loose channel 57 by the movement of the mold-cover 2 and slidable jaw bar 36 toward the left. 110

What is claimed is:

1. The combination in a type-casting machine of members forming a tight channel to receive type, one of said members being cut away adjacent the receiving end of said 115 tight channel to a depth sufficient to take in several type whereby a loose channel is provided to first receive the type, movable jaw members adapted to transfer a molded type to said loose channel, and a plunger for pushing the type into and through said channels. 120

2. The combination in a type-casting machine of movable jaw members adapted to transfer a molded type to a point over the 125 channel of the machine, a plunger, means for moving said plunger to force type through the said channel, a nick guide, a member co-acting with the nick guide to form the said channel, the said member being 130

beveled at its type receiving end to a depth sufficient to take in several type so as to provide a loose channel in which the type are first received, and a tight channel into and through which the type are pushed by the plunger.

3. The combination in a type casting machine of a reciprocative mold-cover, a plunger carried thereby, means for positively moving said plunger in one direction, a mold, a clamp for clamping said mold-cover against said mold, and a member carried by said clamp for positively moving said plunger in the opposite direction.

15 4. The combination in a type-casting machine of a mold, a mold-cover reciprocative thereon, an immovable standard, a rocker arm provided with a boss carried by said standard, a clamp provided with a cylindrical stem passed through an aperture in the boss on said rocker arm, screws carried by said clamp and located on opposite sides of the axis of said stem to cant or turn the clamp, the said clamp being provided with 25 two arms adapted to press the mold-cover against the mold.

5. The combination in a type-casting machine of a mold, a mold-cover reciprocative thereon, a cage secured to said mold-cover and reciprocative therewith and adapted to inclose the jet on the end of a type, a fixed jet breaker adapted to break the jet from the end of the type, and a jet chute located adjacent to said jet breaker and over which 35 the said cage is adapted to be carried during the reciprocation of the mold-cover to permit the jet broken from the type to fall into said jet chute.

6. The combination in a type-casting machine of a mold-beam provided on its end with a nick guide, a reciprocative mold-cover, a slidable jaw bar, an upright member forming a channel with the nick guide, the top of said upright member being beveled 45 to form a loose channel into which type are adapted to be received, a pusher adapted to push type which may be in the said loose channel toward the said nick guide, means for moving said pusher toward said nick 55 guide, means for limiting the movement of said pusher toward said nick guide, and means for moving said pusher away from said nick guide, the last said means being actuated in unison with the movement of the slidable jaw bar.

7. The combination in a type-casting machine provided with a mold and a channel into which type are transferred from the mold, of movable jaw members for transferring a type from the mold to a point over the said channel, a pusher plate for pushing a type into said channel, means for moving said pusher plate in one direction to push the type into said channel, and means 60 for moving said pusher plate in the oppo-

site direction and retaining the bottom thereof substantially even with the top of the mold.

8. The combination in a type-casting machine provided with a mold and a channel 70 into which type are transferred from the mold, of movable jaw members adapted to transfer a molded type to a point over the channel of the machine, a pusher plate, means for moving said pusher plate in one 75 direction to force a type into the said channel, means for moving said pusher plate in the opposite direction, and means to limit the movement of the pusher plate, when it is being moved in the said opposite direction so that, during a part of the movement of the movable jaw members from said channel toward said mold, the bottom of said pusher plate will be maintained substantially even with the top of the mold. 80

9. In a type casting machine having a type dressing channel, the combination with a mold, reciprocative means for transferring type from the mold to said channel, and a reciprocative pusher plate movable 90 transversely to the movement of said transferring means for forcing the type from the transferring means into said channel, of means for arresting the withdrawal of said plate with its working face close to the 95 opening into said channel as the transferring means is withdrawn toward the mold.

10. In a type casting machine provided with a type dressing channel having a widened receiving end, the combination with a mold, reciprocative means for transferring type from the mold to said channel comprising a slidable jaw bar movable across the opening into said channel and closing the same when said reciprocating means is 100 withdrawn toward the mold, and a reciprocative pusher plate movable transversely to the movement of said reciprocative means into and out of said channel, of means adapted to temporarily arrest the withdrawal of said plate with its working face close to the opening into said channel until said opening is closed by the slidable jaw bar in its return movement. 110

11. In a type casting machine the combination with a mold and reciprocative means for transferring type from the mold, and a nick guide arranged transversely to the travel of said transferring means and forming one wall of a type dressing channel, of a member forming the opposite wall of said channel, said member being cut away to produce an enlargement of said channel at its receiving end and to allow for overthrow of said transferring means and being recessed adjacent to the enlargement of the channel, a pusher inserted in the recess of said member, and means for moving said pusher toward and from the nick guide. 120

12. In a type casting machine, provided 125

with a type dressing channel, the combination with a mold and means for transferring type from the mold to said channel, a reciprocative pusher movable transversely to the movement of said transferring means into and away from said channel, means for thrusting said pusher into said channel, and a spring tending to move the pusher in the opposite direction to the limit of its movement in that direction, of means for posi-

tively withdrawing the pusher from and clear of said channel before the transferring means begins its return movement.

In witness whereof I hereto affix my signature in presence of two witnesses.
